UNITED STATES PATENT OFFICE.

JOHN WOLF, OF TOPEKA, KANSAS.

LATCH-LOCK.

1,336,496.

Specification of Letters Patent. Patented Apr. 13, 1920.

Original application filed April 21, 1919, Serial No. 291,571. Divided and this application filed August 2, 1919. Serial No. 314,960.

To all whom it may concern:

Be it known that I, JOHN WOLF, a citizen of the United States, residing at Topeka, in the county of Shawnee and State of Kansas, have invented certain new and useful Improvements in Latch-Locks, of which the following is a full, clear, and exact description, reference being had to the accompanying drawings, forming a part hereof.

The present is a division of my pending application for patent on trunks, Serial Number 291,571, filed April 21, 1919, being specifically directed to the latch-lock which secures the wardrobe section to the body section of the trunk. The object of the invention is to provide a latch-lock operable from the interior of the trunk to which access is had by first unlocking and opening the lid of the trunk, the lid in the present instance being hinged to the body section and secured to the wardrobe section by any suitable form of key-lock known to the trade. A further object is to provide a latch-lock which is simple, reliable, strong and durable, and one possessing further and other advantages better apparent from the following detailed description in connection with the accompanying drawings in which—

Figure 1 represents a front elevation of a wardrobe trunk showing my invention applied thereto; Fig. 2 is an enlarged outside elevation of the latch-lock; Fig. 3 is an enlarged horizontal section on the line 3—3 of Fig. 1; Fig. 4 is an enlarged horizontal section on the line 4—4 of Fig. 1; Fig. 5 is a vertical cross-section on the line 5—5 of Fig. 2, showing in addition the wall of the wardrobe section; Fig. 6 is an inside elevation of the latch-lock; and Fig. 7 is an inside view of the wall of the wardrobe section showing the elongated slot through which operates the terminal lifting finger of the tripping or pull rod.

Referring to the drawings, 1 represents the body portion or section of the trunk, 2 the wardrobe section, and 3 the top lid hinged to the section 1 and closing against the respective sections. The valance 4 secured to the wardrobe section protects the joint *m* between the sections 1 and 2, the valances 4' carried by the sides of the lid protecting the joints *m'* between the lid and wardrobe section, the lid being locked to the latter section by any suitable form of key-lock 5, all as fully understood in the art.

Secured to the wardrobe section 2 near the bottom of the trunk, opposite the hinge axis between the sections 1 and 2 (said sections being hinged in the back as well understood in the art), is the latch-lock L (Fig. 1), the same being a keyless lock and operable only from the inside of the trunk after the lid 3 has been swung to open position. The lock comprises a casing or member 6 secured to the front of the wardrobe section 2 adjacent the free vertical edge thereof, and a keeper member 7 secured to the section 1 in position to coöperate with the casing. The casing is provided with a bridge-piece or plate *w* spanning the open side of the casing and engaging the wall of the wardrobe section 2 (Fig. 5), said bridge-piece supporting one end of a pivot pin *d* extending across the casing, the opposite end of the pin being supported in the outer wall of the casing. Mounted pivotally on the pin *d* is the vertically oscillating latch 8 forming a lever of the first class. One arm of the latch lever terminates in a locking finger *h* which is normally held in engagement with the catch or keeper *t* of the member 7 by a flexed spring 9 bearing with its free end against the opposite arm of the latch, the fixed end of the spring being secured to the casing 6 at the side of one of the outer terminal tongues *a*, *a*, thereof, said tongues being received in the chamber *b* of the member 7 when the sections 1 and 2 are swung to closed position. The tongues *a*, *a*, serve to guide the latch into the chamber *b* and into locking position with the keeper with a closing movement of the wardrobe section, the coacting bevel faces of the latch and keeper permitting the latch to lock automatically with the keeper when the wardrobe section is fully closed.

As previously pointed out, the lock L is keyless and is operated from the inside of the trunk. For this purpose I provide a sliding tripping rod 10 held loosely to the wall of the section 2 by means of a series of straps 11, the lower end of the rod being bent outwardly to form an arm or lifting finger 10' traversing a vertically elongated slot 12 in the wall of said section 2, said finger bearing against the bottom edge of the spring-controlled lever arm of the latch 8, that is to say, the edge opposite from that engaged by the free end of the flexed spring 9. The upper end of the tripping

rod is provided with a finger hold or eye *e* by which it may be manipulated. It is obvious that by seizing the eye *e* and pulling on the rod the finger 10' thereof will lift the 5 adjacent lever arm of the latch, thereby depressing the locking finger *h* and releasing the latter from the keeper *t* (dotted position, Fig. 6). This leaves the section 2 free to be swung to open position. The rod 10 terminates at the top in close proximity 10 to the upper end of the wardrobe section 2 so that the eye *e* thereof is within easy and ready reach of the operator the moment the lid 3 is swung to open position. After the 15 rod 10 is released the spring 9 of course restores the latch to its normal position; and when the wardrobe section 2 is subsequently closed the inclined riding surfaces of the finger *h* and keeper *t* will permit the finger 20 to pass behind the keeper, and automatically lock therewith under the action of the spring 9 as well understood in the art. Features shown but not alluded to are either well known in the art or form subject-matter 25 for independent applications for patent. Obviously, the lock is not limited in its application to trunks, but may be used wherever a latch-lock can be of service.

Having described my invention what I 30 claim is—

A lock of the character described com-

prising a casing, a bridge-piece spanning the open side of the casing, a latch-lever of the first class pivotally mounted in the casing between the bridge-piece and outer wall of 35 the casing and oscillating in the plane of the bridge-piece, a locking finger at the free end of one arm of the latch-lever, tongues on the sides of the casing projecting beyond the open end of the casing, a flexed spring in the 40 casing behind the bridge-piece having one end secured to the casing on the inner side of one of the tongues, the free end of the spring bearing against one side of the opposite lever arm of the latch, a tripping rod 45 terminating at one end in a finger engaging the opposite side of said lever arm, a keeper member, a chamber in the keeper member for receiving and guiding the tongues and latch lever of the casing, and a catch on the 50 keeper at the open side of the chamber thereof disposed across the plane of disposition of the tongues for engaging the locking finger of the latch, the tongues being disposed in the general plane of, and ex- 55 tending beyond, the bridge-piece.

In testimony whereof I affix my signature, in presence of two witnesses.

JOHN WOLF.
